ABSTRACT: A textile beam includes a substantially cylindrical tube having internal threads at the opposite ends thereof. A pair of heads are each provided with hubs having external threads thereon which are threaded within opposite ends of the tube. The threads on the tube and heads include opposite flanks extending at oblique angles to the longitudinal axis of the tube. Abutting surfaces are formed on the ends of the tube and each of the heads. These abutting surfaces are preloaded in an axial direction parallel with the longitudinal axis of the tube and extend parallel with or are an extension of a line from the joint between the abutting surfaces and the center of deflection of the associated head. Each end of the tube is beveled, and the abutting surface formed on each of the heads joins with an annular surface of arcuate cross-sectional configuration.

TEXTILE BEAM

BACKGROUND OF THE INVENTION

The present invention relates to a textile beam or so-called warp beam employed in the textile industry and upon which yarn is wound for subsequent handling and use in the fabrication of a finished article.

Textile beams of this type employ a pair of heads secured to opposite ends of a tube. When the yarn is wound on the beam, the load on the heads increases to such an extend that it tends to cause deflection of the heads. Such deflection, in turn, produces separation of the abutting surfaces between the heads and the tube whereby yarn filaments can enter the space created by such separation causing a considerable loss of yarn due to the fact that parts of the yarn become trapped between the head and tube of a beam.

In order to prevent separation of the head of the textile from an associated tube, various approaches have been employed in the prior art. As shown, for example, in U.S. Pat. No. 2,683,573, the heads are threaded onto the associated tube, and buttress-type threads are provided on the cooperating elements so as to resist separation of the heads from the tube.

In another arrangement as shown, for example, in U.S. Pat. No. 3,317,160, the abutting surfaces on the heads and the tube are formed substantially perpendicular to a line extending from the joint defined by the abutting surfaces to the center of deflection of the head. With such a construction, any deflection of the head with respect to the associated tube results in sliding movement between the abutting surfaces of the joint rather than separating movement.

SUMMARY OF THE INVENTION

In the present invention, a construction is employed wherein it is not necessary to utilize buttress-type threads, and a conventional Acme-type thread is employed in combination with a novel orientation of the abutting surfaces formed on the tube and the associated heads.

In the present invention, torque is applied to the head during assembly so that the abutting surfaces formed on the tube and the heads are preloaded in an axial direction parallel with the longitudinal axis of the tube. This preload must be overcome by the force of the yarn wound on the beam before any opening or separation of the abutting surfaces at the joints between the tube and the heads can occur.

The abutting surfaces formed on the tube and each head in the present invention are parallel with or are an extension of a line extending from the joint between the abutting surfaces to the center of deflection of the associated head.

The abutting surface formed at each end of the tube is substantially frustoconical and tapers inwardly from the outer surface of the tube toward the end of the tube. Each of these abutting surfaces forms an angle of approximately 135° with respect to the yarn retaining face formed on the radially outwardly extending flange of the associated head.

A surface is formed on the tube adjacent each of the abutting surfaces thereof, each of these adjacent surfaces being substantially frustoconical and flaring radially outwardly from the inner surface of the tube toward the end of the tube and intersecting the associated abutting surfaces on the tube.

The abutting surface formed on each of the heads is also frustoconical and is complementary to the frustoconical abutting surface formed on an end of the tube. The abutting surfaces on each head taper radially inwardly away from the inner end of the associated head and also form an angle of approximately 135° with respect to the yarn retaining face on the associated head.

Each head also has a surface formed thereon adjacent the abutting surface thereof, said adjacent surface on each head being annular and substantially arcuate in cross-sectional configuration.

With the aforementioned construction, torque may be applied to each head during assembly thereof, and as a result of

such torque and lubrication applied to the cooperating threads on the tube and the head, and the abutting surfaces of the joint can be preloaded in an axial direction parallel with the longitudinal axis of the tube.

BRIEF DESCRIPTION OF THE DRAWINGS

FIG. 1 is a view partly broken away and in section of a textile beam according to the present invention;

FIG. 2 is a view on an enlarged scale of a portion of the structure shown in FIG. 1 with the parts in a different relative position with respect to one another;

FIG. 3 is an enlarged view illustrating the cooperating threads employed on the tube and head of the beam;

FIG. 4 is a sectional view of a modified form of the invention; and

FIG. 5 is a sectional view similar to FIG. 4 illustrating still another form of the invention.

DESCRIPTION OF THE PREFERRED EMBODIMENTS

Referring now to the drawings wherein like reference characters designate corresponding parts throughout the several views, the textile beam of the present invention includes a tube 10 having a pair of identical heads 12 secured to opposite ends thereof. Tube 10 is substantially cylindrical in configuration and has a longitudinal axis X-X. The tube includes an inner surface 13 and concentric outer surface 14, internal threads 16 being formed in the inner surface 13 at opposite ends of the tube.

It should be understood that the opposite ends of the tube are of identical configuration and cooperate in a similar manner with the associated heads. As seen in FIG. 2, each end of the tube includes an abutting surface 20 which is of substantially frustoconical configuration and tapers radially inwardly from the outer surface 14 of the tube toward the end of the tube.

Each end of the tube is also provided with an adjacent surface 22 which is frustoconical in configuration and flares outwardly from the inner surface 13 of the tube toward the end of the tube and intersects abutting surface 20.

Each head includes a hub portion 30 having a radially outwardly extending flange 32 extending therefrom, this flange defining a yarn retaining face 34 at one side thereof. A bore 40 is formed through the hub of each head, and the usual grooves 42 disposed at diametrically opposite sides of the bore are provided for operatively connecting the beam with an associated spindle.

External threads 50 are formed on the outer surface of hub 30, and the details of the threads formed on the hub and the tube are illustrated in FIG. 3. The threads comprise a modified eight pitch Acme thread wherein the thread flanks define an angle "a" of 14½°. The thread flanks 16' at one side of the threads formed on the tube are in contact with the thread flanks 50' at one side of the threads formed on the associated head, while the thread flanks 16'' at the opposite side of the threads formed on the tube are spaced from the flanks 50'' on the opposite sides of the threads formed on the associated head. The engagement of flanks 16' and 50' with one another resists separation of the abutting surfaces of the tube and associated heads.

Each head includes an abutting surface 60 which is of frustoconical configuration and tapers radially inwardly away from the inner end 62 of the head. Abutting surface 60 is complementary to abutting surface 20, and when in assembled relationship as shown in FIG. 1, these surfaces snugly engage one another and form an angle "b" of approximately 135° with respect to the yarn retaining face 34 of the associated head.

The center of deflection of head 12 is indicated by dot 70 which represents a circular line located on the neutral axis of the beam near the location of maximum bending. The location of this neutral axis is a function of the dimensions of the beam and does not change with the yarn load applied to the beam. Abutting surfaces 60 and 20 are parallel with or from an ex-

tension of a line extending from the joint between the abutting surfaces to the center of deflection of the head.

Each head also includes a surface 74 joining with surface 60, surface 74 being annular and of substantially arcuate cross-sectional configuration.

When each head is assembled on the associated tube, lubrication is applied to the threads on the tube and the head, and torque is applied to the head so as to preload the abutting surfaces of the joint in an axial direction extending substantially parallel with the longitudinal axis of the tube.

Referring now to FIG. 4 of the drawings, a modification is illustrated wherein the major portions of the structure are similar to that previously described and corresponding parts have been given the same reference numerals primed. The only difference in the structure shown in FIG. 4 from that previously described is the provision of additional abutting surfaces 80 and 82 formed on the tube and the head respectively. Surfaces 80 and 82 are spaced axially from the aforesaid abutting surfaces 20' and 60', and abutting surfaces 80 and 82 are each of frustoconical configuration and complementary to one another.

Referring now to FIG. 5, a further modification is illustrated. This embodiment of the invention incorporates abutting surfaces 90 and 92 formed on the tube and the head respectively. Abutting surfaces 90 and 92 extend substantially perpendicular to the longitudinal axis of the tube.

As this invention may be embodied in several forms without departing from the spirit or essential characteristics thereof, the present embodiment is therefore illustrative and not restrictive, since the scope of the invention is defined by the appended claims rather than by the description preceding them, and all changes that fall within the metes and bounds of the claims or that form their functional as well as conjointly cooperative equivalents, are therefore intended to be embraced by those claims.

I claim:

1. A textile beam comprising a tube, a pair of heads one of which is secured to each end of said tube, each end of the tube and the adjacent head having abutting surfaces formed thereon to define a joint, said tube and each of said heads having cooperating threads formed thereon to secure the heads in place, said threads having opposite flanks disposed at oblique angles to the longitudinal axis of said tube, the abutting surfaces between each of said heads and an associated end of the tube being preloaded in an axial direction extending parallel with the longitudinal axis of said tube, and the abutting surfaces at the joint between each of said heads and the associated end of the tube being parallel with or an extension of a line extending from the joint to the center of deflection of the associated head.

2. Apparatus as defined in claim 1, wherein the abutting surfaces formed on said tube and said heads are substantially frustoconical in configuration.

3. Apparatus as defined in claim 2, wherein the frustoconical surface at each end of the tube tapers radially inwardly from the outer surface of the tube toward the associated end of the tube, the abutting surface formed on each head tapering inwardly away from the inner end of the associated head.

4. Apparatus as defined in claim 3, wherein each of said heads includes a radially outwardly extending flange having a yarn retaining face disposed on one side thereof, the abutting

surfaces formed on said tube and said head extending at an angle of approximately 135° with respect to the yarn retaining face of the associated head.

5. Apparatus as defined in claim 2, wherein said tube includes a surface formed adjacent each of the abutting surfaces thereon, each of said adjacent surfaces being substantially frustoconical and flaring radially outwardly from the inner surface of the tube toward the end of the tube and intersecting the associated abutting surface.

10 6. Apparatus as defined in claim 1, wherein each of said heads has a surface formed thereon adjacent the abutting surface thereof, said adjacent surface being annular and of substantially arcuate cross-sectional configuration.

7. Apparatus as defined in claim 1, wherein the abutting surface formed at each end of the tube is substantially frustoconical in configuration and tapers radially inwardly from the outer surface of the tube toward the associated end of the tube, the abutting surface formed on each of said heads being of frustoconical configuration and tapering radially inwardly away from the inner end of the associated head, said tube having a surface disposed adjacent each of said abutting surfaces, each of said adjacent surfaces on the tube being substantially frustoconical and flaring radially outwardly from the inner surface of the tube toward the associated end of the tube, each of said heads having a surface formed thereon adjacent the abutting surface on the head, each of said adjacent surfaces on the head being annular and of substantially arcuate cross-sectional configuration.

8. Apparatus as defined in claim 1, wherein said tube has a further pair of abutting surfaces formed thereon, each of said heads having a further abutting surface thereon engageable with one of said further abutting surfaces on the tube, said further abutting surfaces formed on the tube and each of said heads being spaced axially from said first mentioned abutting surfaces and extending at an oblique angle to the longitudinal axis of the tube.

9. Apparatus as defined in claim 1, wherein said tube has a further pair of abutting surfaces formed thereon, each of said heads having a further abutting surface thereon engageable with one of said further abutting surfaces on the tube, said further abutting surfaces formed on the tube and each of said heads being spaced axially from said first mentioned abutting surfaces and extending substantially perpendicularly to the longitudinal axis of the tube.

10. A textile beam comprising a tube, a pair of heads one of which is secured to each end of said tube, each end of the tube and the adjacent head having abutting surfaces formed thereon to define a joint, said tube and each of said heads having cooperating threads formed thereon to secure the heads in place, said threads having opposite flanks disposed at oblique angles to the longitudinal axis of said tube, with the thread flanks at one side of the threads on the tube in contact with the thread flanks at one side of the threads on the heads, and with the thread flanks at the opposite side of the threads on the tube spaced from the flanks on the opposite sides of the threads on the heads, said threads resisting separation of the abutted surfaces of the tube and their associated heads, the abutting surfaces between each of said heads and an associated end of the tube being preloaded in an axial direction extending parallel with the longitudinal axis of said tube.
